UNITED STATES PATENT OFFICE.

JAMES M. WASSON AND MICHAEL E. CAHN, OF NEW ORLEANS, LOUISIANA.

APPARATUS FOR LIFTING LIQUIDS.

1,200,402.

Specification of Letters Patent.

Patented Oct. 3, 1916.

Application filed December 29, 1915. Serial No. 69,205.

To all whom it may concern:

Be it known that we, JAMES M. WASSON and MICHAEL E. CAHN, citizens of the United States, residing at New Orleans, in the parish of Orleans and State of Louisiana, have invented certain new and useful Improvements in Apparatus for Lifting Liquids; and we do hereby declare the following to be a full, clear, and exact description of the invention, such as will enable others skilled in the art to which it appertains to make and use the same.

Our invention relates to improvements in apparatus for lifting liquids, especially for lifting water, oil, or other liquids from wells.

It is quite common in Artesian or oil wells that the liquid will rise to a considerable height inside the well casing, but has to be lifted through a comparatively short distance to the surface of the ground, or to the point of distribution. This additional lift is accomplished in a variety of ways, such as by force pumps, air jets, or the like, and our invention is intended to provide an improvement on the apparatus by means of which the liquid is lifted through the use of an air jet, or a series of air jets.

Our invention will be more clearly understood after reference to the accompanying drawings, in which the same parts are indicated by the same reference symbols throughout the several views, and in which:—

Figure 1 shows a section through the well casing, and shows the other parts of the apparatus in elevation, with the air compressor shown diagrammatically; Fig. 2 is a detail showing the lower section of the pipe for conveying compressed air to the system, the delivery nozzles being removed therefrom; Fig. 3 is a section along the line 3—3 of Fig. 1, parts being shown on a larger scale; Fig. 4 is a detail showing a front view of one of the air nozzles as detached from the apparatus, parts being shown on a still larger scale; and Fig. 5 shows a section along the line 5—5 of Fig. 4, and looking in the direction of the arrows.

A represents the well casing constructed in the usual way, and provided with a screen or screens *a* and *a'* at the bottom thereof. It may also be provided with a

closed top B, if desired, or the top may be left open.

C represents the pipe for delivering the liquid, which is controlled by the valve *c*. D represents the air compressor connected by a suitable coupling, such as E, to the air delivery pipe F, controlled by the valve *f*. The lower section F' of this pipe F is closed at its lower end by a suitable cap or plug *f'*, and is provided with a series of internally screw-threaded openings *f* which are preferably arranged in the staggered relation as shown in Figs. 1, 2 and 3. Into these screw-threaded openings *f* the necks *g* of the nozzles G are screwed, which nozzles are preferably provided with expanding chambers *g'*, and covered with the cap H provided with a series of apertures *h* therein, as shown most clearly in Figs. 4 and 5. These nozzles are arranged as shown in Fig. 3 to impart a vortical direction to the air currents issuing therefrom, and consequently to create a whirl in the water for purposes hereinafter described. Compressed air may be supplied to the air compressor in any convenient way, or storage flasks may be used if desired. The location of the section F' of the air pipe should preferably be about three times as far below the static head of liquid in the well as the static head of liquid in the well is below the delivery pipe C, so that the apparatus will operate efficiently; although under certain conditions it may be more advantageous to locate the nozzles at a still lower comparative depth.

The operation of the device is as follows: Air under pressure being contained in the air compressor, the valve *f* is opened, turning the air pressure on the pipe F, and the valve *c* is opened to permit the escape of the liquid as it rises in the well casing. Air rushing down through the pipe F will enter the nozzle section F' and, escaping into the nozzles G, will extend into the chamber *g'* and will pass through the series of openings *h* in the cap H, and will enter the liquid in a series of finely distributed streams of air, and at a tangent to the circle formed by said nozzle outlets. Moreover, the air being under compression will tend to force the liquid upward, as well as to lift the same owing to its lesser specific gravity, and the spiral motion of the air and liquid will in a measure tend to prevent air from

escaping upwardly through the liquid without exercising an adequate lifting effect thereon. By having a large number of minute air jets impart this vertical motion to the liquid, as shown, great efficiency of the air in lifting the liquid is secured. By having the nozzles connected to the pipe F' in staggered relation, as shown, the escaping air is better distributed through the liquid, and moreover said pipe F' is not materially weakened as would be the case if the perforations were grouped in the same horizontal plane.

The length of the pipe section F' and the number and disposition of the nozzles G may be varied to suit varying requirements of the apparatus, and this pipe section F' may be raised or lowered relative to the static head of the liquid in the well, according to the special conditions.

It will be obvious that various modifications might be made in our device, and in the construction, combination and arrangement of the parts constituting the same which might be used without departing from the spirit of our invention.

Having thus described our invention what we claim and desire to secure by Letters Patent of the United States is:—

30 1. Apparatus for lifting liquids, comprising a cylindrical casing, an air pipe projecting down into said cylindrical casing and provided with a series of tangentially disposed curved expanding nozzles projecting therefrom, and means for supplying compressed air to said air pipe, substantially as described.

40 2. Apparatus for lifting liquids, comprising a cylindrical casing, an air pipe projecting down into said cylindrical casing and provided with a series of tangentially disposed nozzles projecting therefrom, said nozzles being arranged in the staggered relation relative to said pipe, and means for 45 supplying compressed air to said air pipe, substantially as described.

3. Apparatus for lifting liquids, comprising a cylindrical casing, an air pipe projecting down into said cylindrical casing and provided with a series of tangentially disposed curved expanding nozzles projecting therefrom, said nozzles being arranged in the staggered relation relative to said pipe, and means for supplying compressed air to said air pipe, substantially as described.

4. Apparatus for lifting liquids, comprising a cylindrical casing, an air pipe projecting down into said cylindrical casing and provided with a series of tangentially disposed curved expanding nozzles projecting therefrom, each of said nozzles being provided with a cap having a series of perforations therethrough, and means for supplying compressed air to said air pipe, substantially as described.

5. Apparatus for lifting liquids, comprising a cylindrical casing, an air pipe projecting down into said cylindrical casing and provided with a series of tangentially disposed nozzles projecting therefrom, said nozzles being arranged in the staggered relation relative to said pipe, and each of said nozzles being provided with a cap having a series of perforations therethrough, and means for supplying compressed air to said air pipe, substantially as described.

6. Apparatus for lifting liquids, comprising a cylindrical casing, an air pipe projecting down into said cylindrical casing and provided with a series of tangentially disposed curved expanding nozzles projecting therefrom, said nozzles being arranged in the staggered relation relative to said pipe, and each of said nozzles being provided with a cap having a series of perforations therethrough, and means for supplying compressed air to said air pipe, substantially as described.

In testimony whereof, we affix our signatures.

JAMES M. WASSON.
MICHAEL E. CAHN.
